(57) **CLAIM**

The ornamental design for a wireless IC tag, as shown and described.

DESCRIPTION

FIG. 1 is a front elevational view of a first embodiment of a wireless IC tag according to our new design. A rear elevational view thereof is a mirror-image of the front elevational view.

FIG. 2 is a right side elevational view thereof.

FIG. 3 is a left side elevational view thereof.

FIG. 4 is a top plan view thereof.

FIG. 5 is a cross-sectional view thereof, taken in the direction of line 5-5 in FIG. 4.

FIG. 6 is a bottom plan view thereof.

FIG. 7 is a perspective view thereof.

FIG. 8 is a front elevational view of a second embodiment of a wireless IC tag according to our new design. a rear elevational view thereof is a mirror-image of the front elevational view.

FIG. 9 is a right side elevational view thereof.

FIG. 10 is a left side elevational view thereof.

FIG. 11 is a top plan view thereof.

FIG. 12 is a bottom plan view thereof; and,

FIG. 13 is a perspective view thereof.

The broken line shown in FIG. 4 indicates a plane upon which the sectional view in FIG. 5 is taken and forms no part of the claimed design.
